UNITED STATES PATENT OFFICE.

CHARLES B. IRISH, OF GRAND ISLE, VERMONT.

FRUIT-EVAPORATOR.

SPECIFICATION forming part of Letters Patent No. 273,091, dated February 27, 1883.

Application filed November 8, 1882. (No model.)

To all whom it may concern:

Be it known that I, CHARLES B. IRISH, a citizen of the United States, and a resident of Grand Isle, in the county of Grand Isle and State of Vermont, have invented a new and valuable Improvement in Fruit-Evaporators; and I do hereby declare that the following is a full, clear, and exact description of the construction and operation of the same, reference 10 being had to the annexed drawing, making a part of this specification, and to the letters and figures of reference marked thereon.

The figure of the drawing is a vertical sectional view of my device.

15 This invention has relation to apparatus for evaporating the moisture from fruit; and it consists in the construction and novel arrangement of a close, hollow base-pan, having above it a series of close, hollow shelves, supported 20 by intermediate upright central tubes, forming passages communicating with the chambers of the shelves and in line with an upper feeding vessel or drum, forming an entire hollow-shelved vessel, and in connection therewith an 25 open-bottom covering or jacket designed to envelop the entire vessel.

The invention also consists, in combination with the shelved hollow vessel and its jacket, of movable perforated under shelves, suspended 30 from the hollow main shelves, in position close to the bottoms thereof, all as hereinafter set forth, and particularly pointed out in the appended claims.

In the accompanying drawing, the letter A 35 designates a hollow-shelved vessel, which is constructed entire, and consists of a close base-pan, *a*, made deep enough to hold a sufficient quantity of water for the purpose hereinafter described, close hollow shelves *b*, of less depth 40 than the base-pan, short central supporting-tubes, *c*, and the upper feeding vessel or funnel, *d*. The hollow shelves have each a top, *e*, bottom *g*, and side wall *h*, and are arranged one above another in series, being supported in 45 position by the intermediate short tubes, *c*, which form passages *k*, communicating with the hollow chambers *l* of the shelves, the lower tube communicating with the hollow interior of the base-pan, from the center of the top of 50 which it extends upward, supporting the lower shelf of the series. The tubes *c* are in line

with each other vertically, and are also in line with the upper drum or feeding-funnel *d*, with the interior of which the upper tube is in communication. This feeding drum or funnel is 55 provided with a cover, *m*, which is also provided with a small funnel, *n*, for convenience in pouring small quantities of water down into the interior of the shelved vessel. The outer edges of the hollow shelves are usually connected to each other and to the upper drum, *d*, by means of bracing-strips *s*, which serve to strengthen the structure and aid in keeping the shelves in proper horizontal position when loaded. 60

65 *B* represents the enveloping-jacket, which is in general form similar to the vessel *A*, but large enough to cover it completely. Its bottom is open and its upper portion is conical or tapering, and is made with an opening, *p*, at 70 top for the escape of the moisture from the fruit on the shelves.

75 *C* indicates the under shelves, which are made in pan shape, having side walls *v* and perforated bottoms *z*. These shelves have central openings, *r*, and are placed on the tubes *c* before the latter are connected to the hollow shelves. The under shelves are movable on the tubes, and are held up in close relation to the bottoms of the hollow shelves by movable 80 catches *t*. When fruit is to be placed on one of these under shelves, the catches are unfastened and the under shelf lowered upon the shelf below. The fruit is then placed upon the perforated bottom and the under shelf is 85 raised up in close relation to the hollow shelf above it, to which it is connected by means of the catches.

The jacket or cover having been placed over the evaporating-vessel *A*, heat is applied by 90 means of hot water or steam. If hot water is used, the vessel should be filled therewith. If steam is employed, sufficient water should be introduced into the base-pan to generate the steam, when the vessel and its cover are placed 95 upon a suitable furnace or heater.

This evaporator is of simple construction, and can be used with the greatest facility.

When the jacket is removed, access is had to the shelves from all sides. A single central 100 passage serves for the introduction of water and for the escape of steam. By means of

the under shelves the bottoms of the heated hollow shelves are utilized, so that each shelf has a double capacity.

Having described this invention, what I claim, and desire to secure by Letters Patent, is—

1. The close, hollow base-pan *a*, having above it a series of close, hollow shelves, *b*, supported by intermediate upright central tubes, *c*, forming passages *k*, communicating with the chambers *l* of the shelves, and in line with an upper feeding vessel or drum, *d*, the whole forming an entire hollow-shelved vessel, substantially as specified.

2. The combination, with the hollow-shelved vessel *A*, having the base-pan and central

tubes supporting the shelves, of the open-bottom enveloping-jacket *B*, having an opening at its top, substantially as specified.

3. The combination, with the hollow-shelved vessel *A* and its enveloping-jacket *B*, of the movable perforated under shelves, *C*, suspended by catches from the hollow main shelves, in position close to the bottoms thereof, substantially as specified.

In testimony that I claim the above I have hereunto subscribed my name in the presence of two witnesses.

CHARLES B. IRISH.
